EMIL SCHNELL AND PHILIP SCHNELL, OF GLENDALE, LONG ISLAND, NEW YORK

LAUNDRY-MACHINERY LOCK

Application filed March 31, 1927. Serial No. 179,999.

This invention relates to locks and safety devices particularly adapted for use in connection with laundry machinery.

In laundries employing a great number 5 of workers and machines adapted for the washing and drying of clothes comprising high speed rotating parts into which the clothes are placed for washing and drying, it has been a problem to prevent the operators 10 of the various machines from trying to remove the clothes from the machines when the same are in operation and to also prevent the starting of the machine before the covers thereof are securely locked.

15 A particular object of our invention, therefore, is to provide a lock for the cover of extractors, washing machines and the like which will only operate when the revolving interior part of the machine comes to a stop.

20 We are aware that many devices have been used which contemplate the locking of the cover until the belt has been shifted to throw the power off the machine, but in an agitator, for instance, where an inner basket is rotating 25 at high speed, the inertia thereof maintains rotation for considerable time after the belt has been shifted to the idle pulley on the drive shaft with the result that the cover can open after the belt has been so shifted and in many 30 instances serious injury has resulted when an operator endeavored to remove the clothes or to extract the basket before the same has stopped. This is also true of the drum-type washers having revolving compartments 35 which hold individual bundles of clothes to be washed and a further particular object of our invention is to provide a device which is equally adaptable for the drum-type washing machine or in fact to any other machine employing 40 slideable covers and operated directly from the power shaft.

A further particular object of our invention is to provide a fluid control lock which is operated directly by the driving shaft so 45 that the cover is prevented from being raised until the driving shaft comes to rest.

To enable others skilled in the art to fully comprehend the underlying features of our invention that they may embody the same 50 in the various modifications in structure and

relation contemplated, a drawing depicting a preferred form has been annexed as a part of this disclosure and in such drawings, similar reference characters denote corresponding parts throughout all the views, of which, 55

Figure 1 is a view in side elevation of an extractor having a hinged cover and showing in combination therewith our improved fluid operated lock which prevents the cover from being raised while the interior basket of the 60 extractor is in motion.

Figure 2 is a top plan view of the extractor as seen in Figure 1 showing the lock in its locking position to prevent the raising of the 65 cover while the machine is in motion.

Figure 3 is a view in longitudinal section through the locking device showing the construction thereof.

Referring to the drawings in detail, 5 indicates an extractor of the well-known commercial type in which is rotatably mounted the clothes holding basket 6, mounted on the shaft 7 which is driven through the medium of the pulley 8 and its engaging belt 9, the belt passing over a suitable idler 10 and around a drive pulley 11, the drive pulley 11, in turn being mounted upon the driving shaft 12 which carries the idle pulley 13 and the driving pulley 14, the latter of which, as is usually the case, is keyed to the shaft 12 and rotated the same so that a direct drive is accomplished from the source of power through the shaft 12, through the belt 9 to the basket rotating shaft 7, which, as before described, is rotatably mounted within the 70 extractor housing 5. This housing has pivoted thereto by the hinge 15, the cover 16 which allows the clothes held in the basket 6 to be removed from the extractor and replaced by other clothes which have come 75 out of the rinse water and through the centrifugal action imparted thereto by the revolving of the basket 6, are to be dried. This cover 16 is provided at its front with a handle 80 85 and is usually made of heavy wire or steel plate.

One of the objects of our invention is to prevent the opening of this cover while the basket 6 is in motion, as in machines now in use, the cover is unlocked by the throw of 90 95 100

a belt shifter but it is evident that the high rotary speed of the basket 6 will cause its continued spinning after the drive belt has been shifted to the idle pulley 13.

5 In carrying out our invention, we make use of an oil pump 18 which consists of a pair of closely meshing gears 19, the upper one of which is mounted on the end of the drive shaft 12 and the lower of which is mounted on the 10 stub shaft 20 which is carried in the walls of a casing 21 which fits very closely about the periphery of the gears 19, the narrowest point in the casing being at the meshing point of the gears and at this point, we tap the casing on 15 one side to provide an oil inlet 22 which connects the casing with an oil reservoir 23, the latter of which may be replenished, as desired, and which will feed the oil to the pump casing as it is compressed in the conveying 20 pipe line 24 which forms an exit from the opposite side of the casing 21 from the inlet 22, the pipe line 24 being made up of solid pipe or flexible tubing and being connected at its opposite end to the diaphragm chamber 25 of our improved lock. This diaphragm chamber is provided by bolting to the lock housing, as at 26, convex cover 27 through the center of which enters the pipe 24. This cover 27 imprisons between itself and the 30 front wall 28 of the lock housing 29, a thin diaphragm 30, this diaphragm being arranged when distended by oil pressure in the line 24 to cause inward movement of a pin 31 which, at its inner side, is pivoted as at 35 32 to the free arm 33, which extends longitudinally of the casing and at its end adjacent the pivot point 32 rests on a suitable protuberant portion 34 formed in the inner wall of the housing 29 so that the arm 33 is given 40 a point contact which acts as the fulcrum for the lever 33.

The opposite end of the lever 33 engages the locking bolt 35 which is housed in an extended portion 36 of the lock housing 29 and 45 is provided with an enlarged head 37 which abuts against the free end of the lever 33, as hereinbefore described. In order to give a normal retractile movement to the lock bolt 35, the same is encompassed by a spring 38 held in the extended portion 36 and arranged 50 to exert its expanding energy against the head 37. The housing 29 is secured to the top of the extractor through the medium of suitable lugs 39 which are drilled to provide openings for the reception of suitable bolts 40 which hold the lock in place.

It is evident from inspection of Figure 2, particularly, that the extractor shaft being directly connected to the drive shaft 12 will 55 not stop until the drive shaft comes to rest, and as before mentioned, in throwing off the power or shifting the belt to the idle pulley, allow the cover 16 to be raised sometimes causing injury to the operator of the machine when he tried to take clothes out of the

fast revolving basket 6. Our oil pump which is driven directly by the drive shaft 12 maintains a constant pressure of oil in the line 24 and against the diaphragm 30 to cause the extension of the bolt 35 so that it overlies, as 70 shown in Figure 2, the edge of the cover 16 and prevents its being opened while the drive shaft 12 is in motion. This being evident by reason of the fact that the slightest movement of the drive shaft 12 maintains the pressure sufficiently in the oil line 24 to cause distention of the diaphragm to maintain the bolt in its outward position. However, when the drive shaft 12 comes to rest after the driving 75 belt has been shifted, pressure is taken off the oil in the line 24 thus allowing the spring 38 to force the bolt inwardly from over the edge of the cover thereby allowing the same to be opened and the clothes to be removed from the basket 6. It is evident that this arrangement therefore, prevents opening of the cover while the drive shaft 12 is in motion and the same will be kept in motion until the basket 6 stops rotating because the shaft 12 is directly connected to the basket rotating shaft 7 80 through the medium of the belt 9.

It is evident, therefore, that due to the leverage of the lever 33, the short fulcrum thereof, will take cognizance of any movement of the diaphragm 30 and just as soon as 95 the shaft 12 begins to rotate, the oil pressure will cause distention of the diaphragm 30 and cause the lock 35 to be extended to prevent opening of the cover 16.

It is evident, therefore, that we have provided an improved laundry machine cover lock which, it will be particularly noted, is controlled by reason of a direct connection from the driving means to the machine part that is adapted to revolve and therefore, will 100 not permit access to the interior of the machine until such revolving part comes to rest.

It is also evident that we have provided a fluid controlled locking means which is adapted to several different types of washing 110 machines and is made of few parts, will not get out of order and will effectively operate to prevent the raising or sliding of covers on extractors, washing machines, and the like.

While we have illustrated and described 115 our invention with some degree of particularity, we realize that in practice various alterations therein may be made. We therefore reserve the right and privilege of changing the form of the details of construction or 120 otherwise altering the arrangement of the correlated parts without departing from the spirit of the invention or the scope of the appended claims.

Having thus described our invention, what 125 we claim as new and desire to secure by United States Letters Patent is:—

1. The combination with a laundry machine having a cover on the housing thereof and a moving wash holding receptacle in the 130

housing and the wash holding receptacle being driven positively from the drive shaft, of a pump on the drive shaft, a lock casing on the housing connected to the pump, a diaphragm in the casing against which the fluid pressure is transmitted from the pump, a lever movable by said diaphragm and a bolt operable by said lever to overlie the cover when the pressure acts on said diaphragm whereby opening of the cover is prevented

10 until the receptacle comes to rest.

2. The combination with a laundry machine having a cover on the housing thereof and a moving wash holding receptacle in the housing and the wash holding receptacle being driven positively from the drive shaft, of a pump on the drive shaft, a bolt casing on the housing connected to the pump, a movable member in the casing against which the fluid pressure is transmitted from the pump, and a bolt arranged to be projected beyond said bolt casing by said movable member to overlie the cover when the pressure acts on the movable member whereby opening of the cover is prevented until the receptacle comes to rest.

3. The combination with a laundry machine having a cover on the housing thereof and a moving wash holding receptacle in the housing and the wash holding receptacle being driven positively from the drive shaft, of a pump on the drive shaft, the lock casing on the housing connected to the pump, a diaphragm in the casing against which the fluid pressure is transmitted from the pump, a lever movable by said diaphragm and a bolt operable by said lever to overlie the cover when the pressure acts on said diaphragm, and a spring in the housing arranged to act upon said bolt to remove it from over the cover when the pressure on the diaphragm is removed.

4. The combination with a laundry machine having a cover on the housing thereof and a moving wash holding receptacle in the housing and the wash holding receptacle being driven positively from the drive shaft, of a pump on the drive shaft, a bolt casing on the housing connected to the pump, a movable member in the casing against which the fluid pressure is transmitted from the pump, a bolt arranged to be projected beyond the casing by the movable member when pressure is applied to the latter, and means associated with the bolt for retracting the same when pressure is removed from said movable member.

In testimony whereof we affix our signatures.
